CLAIM

The ornamental design for a charger, as shown and described.

DESCRIPTION

FIG. 1 is a front elevational view of a charger showing our new design;

FIG. 2 is a rear elevational view thereof;

FIG. 3 is a left side view thereof;

FIG. 4 is a top plan view thereof;

FIG. 5 is a bottom plan view thereof;

FIG. 6 is a front perspective view thereof; and,

FIG. 7 is a rear perspective view thereof.

The broken lines in the drawings illustrate portions of the charger which form no part of the claimed design. The oblique shade lines in the drawings represent reflective surfaces.
